UNITED STATES PATENT OFFICE.

ARNO A. EWALD AND HERMANN A. EWALD, OF ELGIN, WISCONSIN.

COW-MILKER.

SPECIFICATION forming part of Letters Patent No. 693,850, dated February 25, 1902.

Application filed June 5, 1901. Serial No. 63,261. (No model.)

To all whom it may concern:

Be it known that we, ARNO A. EWALD and HERMANN A. EWALD, citizens of the United States, residing at Elgin, in the county of Dodge, State of Wisconsin, have invented certain new and useful Improvements in Cow-Milkers; and we do hereby declare the following to be a full, clear, and exact description of the invention, such as will enable others skilled in the art to which it appertains to make and use the same.

This invention relates to milking-machines; and it has for its object to provide a construction wherein by rotation of a crank the several teats will be operated simultaneously to squeeze the milk therefrom, a further object of the invention being to provide a construction wherein the separate milking devices may be adjusted in conformity with the separation of the teats.

Additional objects of the invention are to provide a simple means for holding the milking devices in position and a convenient arrangement of receptacle for the milk.

In the drawings forming a portion of this specification, and in which like numerals of reference indicate similar parts in the several views, Figure 1 is a side elevation showing the complete apparatus. Fig. 2 is an elevation showing the supporting-arm with one of the milkers thereon, the milker being illustrated in its spread position. Fig. 3 is a detailed perspective view of one of the milkers, a portion of the casing being broken away to more clearly show the interior mechanism. Fig. 4 is a top plan view of the support with the milkers removed therefrom.

Referring now to the drawings, the present milker is employed in connection with a stool, including a top 10, having supporting-legs 11, and at one side of which is fixed a mast 12. The mast includes a tubular lower section and an upper section 13, fitted slidably therein, so that it may be raised to different elevations. From the upper section 13 extend two arms 14 and 15, the lower of which is slideable longitudinally of a mast, and with the ends of these arms are pivotally connected the links at one end of lazy-tongs 16, the end portions of the arms 14 and 15 including separate sections pivotally connected for lateral swinging movement and being held in different positions by set-screws, as shown. At the outer end of the lazy-tongs is the main supporting-

casting, including an annular frame 17, having a bracket 18, provided with ears 19 and 20, to which the adjacent end links of the lazy-tongs are pivoted, the ear 20 being mounted for sliding movement toward and away from the ear 19 to conform to the movement of the lazy-tongs. Thus the casting 17 may be moved away from or toward the stool, as may be desired, and may be swung laterally as the occasion may direct. The casting 17 has a number of upwardly-directed fingers 21, spaced at regular intervals, and to each of these fingers is pivoted one of the milking devices, and as these separate milking devices have all the same construction a description of one will suffice for them all. Each milking device then includes a casing comprising a body portion 22, in the form of a boxing, and having a downwardly-extending stem 23, which is directly pivoted to a finger 21, so that the casing may be pivotally moved toward and away from the axis of the casting 17. The body 22 has three sides closed, and the inner face, or the face toward the axis of the casting 17, is open, and parallel with this open face is disposed a transversely-arcuate plate 24, having supporting-legs 25, which extend downwardly and are curved to lie at opposite sides of the bifurcations of the finger 21, and between which bifurcations the stem 23 is pivoted. The plate 24 may thus be moved toward and away from the open inner side of the casing, and the shape of this plate is such that it may conform to the shape of a teat, and on its inner face is provided with a soft covering 26, of rubber or other suitable material, to prevent injury to the teat.

Passed transversely through the body of the casing, at the upper and lower ends thereof, are shafts 27 and 28, and on the shaft 27 are fixed two sprocket-wheels 29, while on the shaft 28 are fixed two additional sprocket-wheels 30, two of the wheels of each set, or rather each wheel of one set, lying in the same plane with the corresponding wheel of the other set, so that they may receive sprocket-chains 31 and 32. Two of the links of each chain are provided with bearings, and in each pair of corresponding bearings is journaled a shaft 33, on which is disposed a drum 34, having a yieldable face 35, there being two of these drums so disposed that when the sprocket-wheels are rotated the drums are moved successively to a point adjacent to the upper end of the arcuate plate

and then carried bodily in a plane parallel therewith, each roller in this parallel movement being adapted to engage the teat and press it with a rolling contact against the 5 arcuate pressure-plate. By this means the milk is squeezed from the teat and is received in a tube 36. The tube 36 is passed upwardly between the legs 25, and the upper portion thereof forms the facing 26 of the arcuate 10 plate, this upper portion being flared and taken over the tops of the sprocket-chains and attached to the side and rear walls of the casing. The teat to be milked is received directly within the upper end of this tube and 15 is held from contact with the sprocket chains and wheels and also from direct contact by the presser-rolls.

To rotate the sprockets to actuate their chains, the shaft 28 has a bevel-gear 37, with 20 which is engaged a corresponding gear 38, carried by a shaft 39, mounted in suitable bearings upon the facing and having a globular gear-wheel 40 at its lower end, which meshes with a corresponding gear 41, mounted upon 25 a spindle on the casting 17, the construction of the globular gear being such as to permit of rotation thereof from the gear 41 in whatever part of its pivotal movement the casing of the milker may be: To rotate the gear 41, 30 a bevel-gear 42 is engaged therewith and is carried by a tumbling-rod 43, connected with an operating crank-shaft 44, having a crank 45. Thus as the crank is operated the presser-rolls of the several milkers are caused to move 35 downwardly of the arcuate plate. If the teats of the cow are far apart, it is of course necessary to spread the group of milkers at the upper ends thereof, and for this purpose a shift-rod 46 is slidably mounted in the casting 17, 40 and at the upper end thereof is a spider 47, the rod being reciprocated to correspondingly move the spider by means of a hand-lever 48, pivoted to the casting 17 and to the shift-rod, said lever having a trigger 49 and pawl for 45 coöperation with a rack 50 to hold the lever in different positions. An angular lever 51 is pivoted to the side of the body 22 of each casting and is in the form of three sides of a parallelogram, the pivot being at the upper 50 corner. The free end of the upper side of this lever 51 is connected with an arm of the spider 47 by means of a connecting-rod 52, while the free end of the lower side is connected pivotally with the corresponding arcuate plate 24. Thus if the spider be raised 55 the several levers 51 will first be actuated to separate the casings and their corresponding pressure-plates, after which the milking devices will be moved pivotally outwardly, so 60 as to spread the upper end of the group.

The several tubes 36 are connected with a trunk-tube 55, having a metallic coupling member 56 at its free end, in which is disposed a glass 57 to show the flow of milk 65 therethrough, and this coupling member is adapted for engagement with a second member 58 upon a second section 59 of the trunk-

tube, through which the milk is discharged to a suitable receptacle.

What is claimed is—

1. A milking device comprising a base having a gear mounted thereon for movement in a horizontal plane, a plurality of milking devices pivoted to the base and each including presser-rolls and a presser-plate adjustable 75 toward and away from the rolls, connections between the rolls and the gear for operating the rolls, a reciprocatory shaft mounted in the base and having a spider having connections with the milking devices and their 80 plates for adjusting the plates and moving the milking devices pivotally when the shaft is reciprocated, and means for reciprocating the shaft.

2. A device of the class described comprising 85 a group of milking devices pivoted for movement of their upper ends toward and away from each other, each milking device including a presser-plate and a presser-roll movable longitudinally thereof, an actuating- 90 gear, a shaft for each milking device operatively connected therewith and having a gear engaged with the actuating-gear, means for rotating the actuating-gear and a single means connected with the milking devices and their 95 presser-plates for adjusting them.

3. A device of the class described comprising 100 a frame having a gear mounted thereon, a plurality of milking devices pivoted to the frame about the gear for movement of their upper ends toward and away from each other, each milking device including an operating-shaft having a globular pinion engaged with the gear, and means for rotating the gear.

4. A device of the class described comprising 105 an annular series of milking devices pivotally mounted for movement of their upper ends toward and away from each other and a single master-gear disposed within the enclosure of the milking devices and in the 110 plane of the centers of pivotal movement thereof and with which all of the milking devices are operatively connected.

5. A device of the class described comprising 115 an annular series of milking devices each including a presser-plate and presser-rolls for coöperation therewith, the said plate being adjustable toward and away from the rolls and the whole number of milking devices being pivotally mounted for movement of their 120 upper ends toward and away from each other, means for actuating the milking devices and a single means connected with the milking devices for simultaneously moving them pivotally and adjusting their presser-plates toward and away from the rolls.

In testimony whereof we hereunto sign our names, in the presence of two subscribing witnesses, on the 14th day of March, 1901.
